CLAIM

I claim the ornamental design of the jewelry pendant, as shown and described.

DESCRIPTION

FIG. 1 is a perspective view of the jewelry pendant.
FIG. 2 is a front elevation view of the jewelry pendant.
FIG. 3 is a right side elevation view of the jewelry pendant.
FIG. 4 is a left side elevation view of the jewelry pendant.
FIG. 5 is a rear elevation view of the jewelry pendant.
FIG. 6 is a top plan view of the jewelry pendant; and,
FIG. 7 is a bottom view of the jewelry pendant.

An exemplary setting is shown in broken lines in the figures.
This setting forms no part of the claimed design.
